J. W. Henderson ~
INVENTOR
BY Victor J. Evans
ATTORNEY

UNITED STATES PATENT OFFICE.

JAMES W. HENDERSON, OF SCRANTON, PENNSYLVANIA.

TICKET HOLDER.

Application filed July 6, 1925. Serial No. 41,844.

This invention relates to ticket holders and has especial application to mine cars and which owing to the construction thereof may be readily and easily and rigidly secured thereto against accidental displacement thereon.

Another object of my invention is the provision of locking means included upon the ticket holder which includes a swinging angle bar having its upper end pivoted to the holder while its opposite end abuts the lower end of the holder to inclose or house the ticket upon the lower end of the holder while a sleeve encircles the angle bar and holder for preventing accidental displacement of the said angle bar from the shoulder included on the holder.

With the above and other objects in view the invention further includes the following novel features and details of construction, to be hereinafter more fully described, illustrated in the accompanying drawing and pointed out in the appended claim.

In the drawing:—

Figure 1 is a fragmentary elevation of a portion of a mine car and showing my present invention applied thereto.

Figure 2 is a vertical sectional view taken through a portion of a mine car and showing the manner in which my present invention may be applied.

Figure 3 is a horizontal sectional view taken on line 3—3 of Figure 1.

Referring to the drawing in detail, wherein like characters of reference denote corresponding parts, the reference character 10 indicates a fragmentary portion of a mine car having an opening 11 drilled therein for the reception of a reduced threaded shank 12 therein which is provided upon the upper portion of a substantially Z-shaped cross section rectangular holder 13. The inner end portion of the reduced threaded shank 12 has included thereon a washer 14 and nut 15 while a cotter pin 16 extends transversely through the inner end portion thereof for preventing the accidental displacement of the said washer 14 and nut 15 in order that the said shank 12 will be held rigidly and against accidental displacement within the opening 11 provided in one side of the mine car. The lower portion of the Z-shaped holder or bar 13 extends upwardly and has included upon one side thereof a shoulder 17, the purpose of which will be

presently apparent. Pivoted as at 18 to the outer side and upon the vertically disposed portion of the holder or bar 13 is a substantially L-shaped swinging lock 19 which when arranged in its normal locked position has its lower offset portion engaging the shoulder 17 provided upon the upper end of the holder or bar 13.

A substantially rectangular shaped locking sleeve 20 is arranged upon the vertically disposed portion of the bar or bracket 13 and which is also adapted for sliding movement upon and receiving therein the substantially L-shaped swinging lock 19 in order that when this locking sleeve 20 is dropped down in the positions as clearly illustrated in Figures 1 and 2 of the drawing, it will be noted that this swinging lock 19 will be held rigidly in the positions as shown and illustrated.

In the process of placing a ticket 21 upon the bracket or bar 13 it is quite obvious that the ticket has included therein a rectangularly shaped opening provided in its upper portion as indicated at 22 in Figure 1 of the drawing. The lower arm of the holder 13 is provided with a recess in the upper face thereof adjacent the body of the holder whereby the ticket is placed on the holder for engaging the same over the upwardly projecting portion of the lower arm of the holder and seating the ticket as shown in Figure 2 so that the upper portion which closes the opening 22 rests in the lower side of the recess 22', and when the said swinging lock 19 is thus arranged in the positions as clearly illustrated in Figures 1 and 2 of the drawing and the locking sleeve 20 slid down upon the vertically disposed portion of the bracket or bar 13, it will be noted that the said ticket 21 will be held against accidental displacement therein.

It is further to be noted that this invention provides an exceedingly useful and advantageous holder for use upon mine cars and other places where tickets are frequently lost in transit and which further, owing to the construction thereof and its adaptability to the mine cars or other vehicles, may be manufactured in great numbers at a very small cost and be readily and easily applied to the respective vehicle in a short time.

The invention is susceptible of various changes in its form, proportions and minor details of construction, and the right is here-

in reserved to make such changes as properly fall within the scope of the appended claim.

Having described my invention what is claimed is:

A device of the character described including a substantially Z-shaped holder having one arm formed with a reduced threaded portion, the other arm formed with a recess 10 in its upper face adjacent the body of the holder, an L-shaped locking lever pivoted upon the body of the holder for lateral swinging movement with respect to the lower horizontal arm of the Z-shaped holder

and adapted to be operatively disposed with its horizontal portion bridging the recess and resting upon the upper face of the said arm, a shoulder on said arm against which the horizontal portion of the L-shaped member abuts to limit the swinging movement 20 of the same in one direction, and a rectangular locking sleeve slidably mounted upon the body of the holder and embracing the vertical portion of the L-shaped member to retain the same in its operative position. 25

In testimony whereof I affix my signature.

JAMES W. HENDERSON.
